[57] **CLAIM**

The ornamental design for a light bulb adaptor for controlling light intensity and the period to reach determined intensity, as shown and described.

DESCRIPTION

FIG. 1 is a front, top and side perspective view of the light bulb adaptor for controlling light intensity and the period to reach determined intensity showing my new design;

FIG. 2 is a side elevational view thereof, all side elevational views being identical to that shown in FIG. 2;

FIG. 3 is a top plan view thereof; and,

FIG. 4 is a bottom plan view thereof.

The two screw threads shown attach to a light bulb screw thread and to a light socket screw thread respectively to interpose the device between the light socket and the light bulb.

FIG.1

FIG. 2

FIG. 3

FIG. 4
